UNITED STATES PATENT OFFICE.

EDWIN C. BALLMAN, OF ST. LOUIS, MISSOURI.

INDUCTION MOTOR.

Application filed January 19, 1920. Serial No. 352,594.

To all whom it may concern:

Be it known that I, EDWIN C. BALLMAN, a citizen of the United States, and residing at St. Louis, Missouri, have invented the new and useful Improvement in Induction Motors, of which the following is a specification.

This invention relates to electric motors, and more particularly to alternating current 10 commutator motors.

There are a number of types of commutator motors at present in use, whose operating characteristics require that the commutator be short circuited after the motor 15 has attained a predetermined speed. The means for effecting such short circuit usually take the form of a series of contactors arranged to make contact with an inner cylindrical surface of the commutator.

20 The arrangements for making and breaking contact are usually such as to produce arcing at the point of making or breaking contact. This has the effect of burning or corrodng the contact surfaces. This results in 25 roughening those surfaces, and as the contacts are usually arranged to slide into and out of engagement, the rough surfaces cause sticking, and consequently, uncertainty of action.

30 One of the objects of this invention, therefore, is to provide improved means for short circuiting the commutator which shall obviate burning and corrosion of the contact surfaces.

35 Another difficulty encountered with the usual construction is that the inner cylindrical contact surface of the commutator is so located as to be inaccessible for cleaning the surface.

40 Another object of this invention, therefore, is to provide short circuiting means making contact with a surface of the commutator accessible for cleaning.

45 Further objects will appear from the following description taken in connection with the accompanying drawings in which:

Figure 1 is a sectional view of a motor embodying this invention;

50 Figure 2 is an enlarged sectional view of the rotor of the above motor;

Figure 3 is an enlarged detail view of the short circuiting conductor and one of the contactors, said contactors being shown in the position assumed at the instant of making or breaking contact; and

55 Figure 4 is a view similar to Figure 3

showing the contactor in the position assumed while maintaining the short circuit.

Referring now to the drawing, 1 designates the stator, and 2 the rotor of an alternating current commutator motor. This rotor has a winding 3 connected to a commutator 4 carried by a commutator support 5. These parts may be of any usual and well known construction and no further description thereof is needed, with the exception that the commutator 4 is provided with a more or less extended radial face 6 adapted to engage a series of contactors 7. The face 6 is preferably located on the front of the commutator so as to be accessible for cleaning without dismantling the motor.

Mounted on the shaft 8 of the motor is a support 9 adapted to slide on said shaft. The support 9 is provided with an annular recess 10 adapted to accommodate a helical spring 11 bearing at one end against the bottom of the recess 10 and at the other end against the commutator support 5. The support 9 is internally threaded to receive the ends of tension rods 12, extending rearwardly therefrom and passing through openings 13 in the commutator support, and similar openings 14 in the body of the rotor. The rearward end of each rod 12 is pivotally connected at 15 with one arm of a bell crank 16 pivoted at 17 on the rotor body, the other arm of the bell crank being provided with a weight 18. The weights 18 are forced radially outward by centrifugal force when the motor runs, and are adapted through the agency of the bell cranks 16 and the rods 12 to move the support 9 rearwardly, when such speed is attained that the centrifugal force of the weights 18 is sufficient to overcome the tension of the spring 11. The support 9 is provided with an abutment 19 adapted, by engagement with the shoulder 20 on the shaft 8, to limit the rearward movement of said support.

100 Mounted on the support 9 is a short circuiting conductor 21 of copper, brass or other suitable conducting material. This conductor has the shape of a flat ring and may be attached to the support 9 by being fitted into an annular recess 22 and spinning over the outer rim of said recess to hold said ring in place or by other suitable means.

The support 9 is further provided with an annular recess 23 adapted to form an annular chamber partially closed by the

conductor 21. The inner wall of the recess 23 takes the form of a barrel extending rearwardly to a point opposite the conductor 21, so as to form a restricted opening 24 for the annular chamber, in which a plurality of contactors 7 are assembled.

Each contactor is provided at one extremity with an enlarged portion 25 at its other extremity with a pair of contact faces 26 and 27. Intermediate the extremities, is a deep recess, the bottom of which forms a pivot portion 28 adapted for engagement with the inner edge of the conductor 21.

These contactors are assembled upon the ring 21 by inserting said ring into the recess up to the pivot portion 28. A sufficient number of these contactors is so assembled to entirely fill up the ring, sufficient looseness being permitted to insure free and unrestricted movement of the contactors. When all of the contactors have been assembled upon the conductor 21, said conductor is assembled upon the support 9 and fixed thereto as previously described. It will be understood that when all the contactors are thus assembled, each will be held in radial position by its neighbors and, the opening 24 being too small to allow the enlarged portion 25 to pass therethrough, the contactors will be permanently assembled on the conductor 21, but will be sufficiently loose to insure free and unrestricted movement about the pivot portion 28.

In operation, when the motor is at a stand still, the spring 11 will move the support 9 forwardly so as to completely disengage the contactors 7 from the face 6 of the commutator. When starting the motor, centrifugal force, acting on the weights 18 will, by the mechanism previously described, move the support 9 rearwardly and bring the contactors 7 into engagement with the face 6 of the commutator. The centrifugal force of rotation acting on the contactors 7 will force them against the conductor 21 at the pivoted point 28 and will, therefore, insure good contact with said conductor. The contactors 7, by making contact with the individual bars of the commutator 4 and with the conductor 21, will short circuit said commutator.

The action of centrifugal force upon the contactors 7 will, when their movement is unrestricted, cause said contactors to assume a position with reference to the conductor 21 as shown in Figure 3. This is due to the fact that the weight of the enlarged portion 25 is greater than that of the opposite extremity of the contactor and, its centrifugal force being greater, the contactor will turn about the pivoted portion 28 in a clockwise direction until stopped by engagement of the portion 25 with the conductor 21. This position will be assumed by all of the contactors as soon as the motor

starts and prior to the engagement of said contactors with the commutator. The contact faces 26 and 27 are so positioned with respect to one another that, with the contactors in the position just described, the face 26 will, upon movement of the support 9, engage the commutator before the face 27. It is obvious, therefore, that whatever arc is to occur upon making contact will occur at the face 26. Upon further movement of the support 9, the contactors 7 will rotate about the pivot portion 28, the contact face 26 sliding outwardly and the contact face 27 laterally coming into engagement with the commutator. The contact faces 26 and 27 are spaced from one another a sufficient distance to insure that the face 27 will engage the commutator at a different point than that of the face 26. Upon completion of the movement of the support 9, the contactors will make the position shown in Figure 4 with the contact face 27 firmly in engagement with the commutator, the portion 25 moved out of engagement with the conductor 21 so that centrifugal force acting on said portion 25 will have the effect of exerting contact pressure both at the pivoted portion 28 and at the face 27. The commutator is, therefore, definitely and positively short circuited.

The support 9 may also be provided with a loose ring 29 adapted upon movement of the support 9 to engage a member 30 on the brush holder to lift the brushes 31 from the commutator.

Upon stopping the motor, the reverse of the above described operations will take place. When the rotor has fallen off sufficiently in speed, the spring 11, overcoming the centrifugal force of the weights 18, will move the support 9 forwardly. Upon such movement, the contactor 7, being still acted upon by centrifugal force, as the motor has not yet come to rest, will rotate in a clockwise direction, (Fig. 3) the contact face 27 sliding radially inwardly until the contact face 26 engages with the commutator, whereupon further movement will disengage the face 27, leaving the face 26 in contact. Still further movement will disengage the face 26, and it will be seen that whatever arcing takes place upon breaking the circuit will again take place at the face 26. It will be seen, therefore, that all the arcing upon making and breaking the circuit will take place at the face 26 and all burning and corrosion will be confined to said face and to its point of engagement with the commutator, leaving the face 27 and its point of engagement perfectly clean and in the best condition to insure a perfect contact.

It will be seen, therefore, that this invention accomplishes its stated objects in providing a short circuiting device in which

the troubles due to burning and corrosion at the contact points are eliminated and the contact surfaces are rendered accessible for cleaning.

5. It is obvious that various changes may be made in the details of the construction of this invention without departing from the spirit of this invention; it is, therefore, to be understood that this invention is not 10 to be limited to the specific details shown and described.

Having thus described this invention, what is claimed is:

1. In an alternating current motor having a commutator, means for short-circuiting said commutator, including a contactor having a contact face, a weight, and a pivot portion intermediate said contact face and said weight, adapted by centrifugal force 20 to move said contactor to contacting position.

2. In an alternating current motor having a commutator, means for short-circuiting said commutator, including a contactor 25 having a contact face, adapted to butt against the commutator, a weight, and a pivot portion intermediate said contact face and said weight, adapted by centrifugal force to apply contacting pressure at and 30 to said contact face.

3. In an alternating current motor having a commutator provided with a radial face, means for short-circuiting said commutator, including a contactor having a 35 contact face adapted to butt against the radial face of the commutator, a weight, and a pivot portion intermediate said contact face and said weight, adapted by centrifugal force to apply contacting pressure to 40 said commutator face.

4. In an alternating current motor having a commutator, means for short-circuiting said commutator, including a contactor having a contact face, a weight and a pivot 45 portion intermediate said contact face and said weight, adapted by centrifugal force to apply contacting pressure both at said contact face and at said pivot portion, said commutator being adapted to engage said 50 contact face, and a conductor adapted to engage said pivot portion.

5. In an alternating current motor provided with a commutator having a considerable number of segments, means for short-circuiting said commutator comprising, a 55 series of contactors, an annular pivot adapted to support said contactors in adjacent annular relation so as to engage the commutator segments, each contactor having a weight portion, a lever portion and a contact face, adapted by centrifugal force 60 of said weight to apply contacting pressure to said contact face, through said lever portion.

6. In an alternating current motor having a commutator, means for short-circuiting said commutator, including, a contactor having two contact faces adapted to engage said commutator, constructed and arranged so that one of said faces will engage before, 70 and disengage after the engagement or disengagement respectively of said other face.

7. In an alternating current motor having a commutator, means for short-circuiting said commutator, including, a contactor 75 having two contact faces adapted to engage said commutator, constructed and arranged so that one of said faces will engage at a different point on said commutator from said other face.

8. In an alternating current motor having a commutator, means for short-circuiting said commutator, adapted to engage said commutator for making and breaking the circuit at one point on said means, and for maintaining the circuit at another point thereon spaced from said first point.

9. In an alternating current motor having a commutator, means for short-circuiting said commutator, comprising, a plurality of contactors each having a notch, a short-circuiting conductor engaging said notches, whereby said contactors may be assembled on said conductor, and a supporting member for said conductor having a part positioned opposite the contactor-engaging portion thereof adapted to maintain said contactors in assembled relation thereon.

10. In an alternating current motor having a commutator, means for short-circuiting said commutator, comprising, a plurality of contactors each having a deep recess, a short-circuiting conductor engaging said recesses, whereby said contactors may be assembled on said conductor, and a supporting member for said conductor having a part positioned to prevent disengagement of said recesses from said conductor, adapted to maintain said contactors in assembled relation on said conductor.

11. In an alternating current motor having a commutator, means for short-circuiting said commutator, comprising, a short-circuiting conductor, a contactor having a recess adapted to engage said conductor whereby said contactor may be assembled thereon, and a supporting member for said conductor, adapted to prevent disengagement of said contactor from said conductor.

12. In an alternating current motor having a commutator, a contactor having a making and breaking contact and a circuit maintaining contact.

In testimony whereof I affix my signature this 19th day of December, 1919.

EDWIN C. BALLMAN.
